UNITED STATES PATENT OFFICE.

ISAAC H. DAVIS, OF BOSTON, AND EDWIN D. MELLEN, OF CAMBRIDGE,
MASSACHUSETTS.

IGNITING-PLUG.

SPECIFICATION forming part of Letters Patent No. 690,640, dated January 7, 1902.

Application filed July 28, 1900. Serial No. 25,082. (No model.)

To all whom it may concern:

Be it known that we, ISAAC H. DAVIS, of Boston, in the county of Suffolk, and EDWIN D. MELLEN, of Cambridge, in the county of Middlesex, in the State of Massachusetts, have invented certain new and useful Improvements in Igniting-Plugs, of which the following is a specification.

This invention relates to plugs employed in igniting devices of the "jump-spark" class for explosive-engines. The invention particularly depends for its novelty on the use of a tapered insulating piece or plug employed in the igniting-plug, whereby the device is simplified and breakage is less likely to occur. In plugs as heretofore constructed considerable difficulty is experienced by the breakage of the central insulating-piece. These plugs are commonly constructed with a socket which screws into the engine-cylinder and a porcelain insulating-piece which is provided with an enlargement or boss at or near its center, which is held to a shoulder on a metallic case, usually with a packing, by means of a metallic nut screwed into the case. Breakage of the porcelain piece takes place on account of the unequal expansion of its different portions due to the heat of the combustion-chamber, and sometimes because the retaining-nut which holds the porcelain piece in the case is screwed down too hard against the shoulder on the said porcelain piece. Our improved construction entirely does away with this faulty construction and the difficulties attending its use.

Of the accompanying drawings, Figure 1 represents a side elevation of an igniting-plug constructed in accordance with our invention. Fig. 2 represents a vertical sectional view thereof. Fig. 3 represents a side elevation of the insulating center piece or plug. Fig. 4 represents a side elevation of a modified form of the said center piece or plug.

The same reference characters indicate the same parts in all the figures.

Referring to the drawings, 1 represents a socket, which is provided on its inner end with a screw-threaded extension adapting the socket to be screwed into the cylinder-wall of

the explosive-engine, the body portion of the socket being preferably formed externally to receive a wrench or similar tool. An electrode 4 is fixed to the inner end of the socket 1, which latter is grounded through the engine-frame.

The socket 1 is provided with a longitudinal frusto-conical bore, in which is fitted a frusto-conical insulating-plug 6, made of a suitable refractory material, such as lava or its equivalent. The plug 6 and its seat within the socket 1 are made to correspond exactly in shape, so as to secure a gas-tight fit. The plug may be driven into the socket to a tight fit, which entirely avoids the use of packing between the plug and socket, such as has heretofore been employed.

7 is the other electrode, between which and the electrode 4 the spark occurs. The electrode 7 is provided with a screw-threaded stem 8, which extends through a longitudinal aperture 9 in the plug 6, and on the outer end of said stem is screwed a nut 11. Said nut bears against a cup-shaped collar 10, which incloses the projecting outer end of the plug 6 and rests upon the outer end of the socket 1. The collar 10 is also made of insulating material and is formed with an aperture 14, through which the stem 8 projects. The nut 11 has a threaded shank 12, upon which a thumb-nut 13 screws, the two nuts forming a binding-post for securing the circuit-wire 17. The electrode 7 is formed as a head on the stem 8, which acts as a shoulder bearing against the inner end of the plug 6. When the nut 11 is screwed down against the collar 10, the plug 6 is then held against any tendency to be jarred or shaken from its seat in the socket. The outer end of the plug 6 projects a considerable distance beyond the outer end of the socket 1 in order to sheath the electrode-stem and prevent the possibility of a short circuit between it and the socket. This necessitates making the collar 10 of a cup shape in order to interpose an abutment between the socket 1 and the nut screwed on the outer end of the electrode-stem.

We have found in practice that a tapered insulating-plug of substantially the character described and mounted in the manner which

we have indicated is much more durable than the hereinbefore-described form of plug in use prior to our invention.

Fig. 4 represents a modified form of the plug 6, in which the inner portion 15 only of the plug is tapered, while the outer portion 16 is substantially cylindrical. This form of plug fits in a metallic socket of corresponding form.

- 10 It will be noted that the vitreous plug or core 6 is characterized by the absence of abrupt projecting shoulders or flanges abutting against any part of the socket 1 or subject to the heat of the cylinder or combustion-chamber. Former cores of igniting-plugs have been subject to fracture not only on account of their having such shoulders located in positions where they would be forced against an unyielding surface by the explosions within 15 the engine-cylinder, but also because of the ununiform and badly-distributed expansions and contractions of a shouldered plug under the influence of its changes in temperature. These causes produce transverse cracks in 20 the plug, usually at the point where the flange or shoulder juts from the body of the plug. A deposit of carbon is then gradually made in this fracture and the plug becomes useless 25 from short-circuiting.
- 30 We claim—
1. An igniting-plug comprising a metallic casing having an aperture with an elongated slight taper formation, a vitreous core characterized by the absence of abrupt projecting

shoulders or flanges and having an elongated 35 slight taper formation complementary to that of the casing-aperture and fitting closely therein and projecting beyond the smaller end of the casing-aperture, a cup-shaped insulating-collar inclosing the projecting end of the 40 core and bearing on the casing around the core, an electrode passing through said core and collar, and a nut screwed on the upper end of the electrode and bearing on the collar to retain the latter and the core and the 45 electrode in their proper relative locations.

2. An igniting-plug for explosive-engines, comprising a metallic socket formed for attachment to the engine, a refractory insulating-plug seated in said socket and its outer 50 end projecting beyond the outer end of the same, an electrode engaged with the insulating-plug and having a threaded stem projecting beyond the outer end thereof, a cup-shaped insulating-collar inclosing the projecting end of the plug and bearing against the outer end of the socket, and a nut screwing on the stem and bearing against the collar, whereby the plug is held to its seat in the 55 socket.

In testimony whereof we have affixed our signatures in presence of two witnesses.

ISAAC H. DAVIS.
EDWIN D. MELLEN.
